CLEANING MACHINE

Charles Hirsch, South Bend, Ind., assignor to
The American Foundry Equipment Company,
Mishawaka, Ind., a corporation of Delaware

Application July 11, 1944, Serial No. 544,374

9 Claims. (Cl. 51—163)

1

The invention relates to cleaning machines of the type used in the industry for the cleaning of machined, cast, molded or surface treated parts made of metal or other materials.

The invention provides a machine for the economical washing and drying of large quantities of relatively small parts in one cleaning chamber.

The invention further provides various features and improvements which are of general application to machines for the cleaning of both small and large parts, resulting in greater efficiency and more economical operation of a machine incorporating these features than was obtainable with conventional equipment.

The features, advantages and details of the invention will appear more fully from the detailed description which follows, accompanied by drawings, showing, for purely illustrative purposes, an embodiment of the invention.

Although the novel features, which are believed to be characteristic of the invention, will be particularly pointed out in the claims appended hereto, the invention itself, its objects and advantages and the manner in which it may be carried out will be better understood by referring to the following description, taken in connection with the accompanying drawings forming a part thereof, in which—

Fig. 1 is an elevational side view, partly in section, of a combination washing and drying machine, embodying the features of this invention.

Fig. 2 is an elevational front view, partly in section, of the machine shown in Fig. 1.

Fig. 3 is an elevational side view of the hot air unit of the machine shown in Figs. 1 and 2.

Fig. 4 is a plan view of a section of a pervious tumbling or conveyor belt used in the machine shown in Figs. 1 and 2.

Fig. 5 is an enlarged sectional front view showing in detail the mounting of the tumbling belt on head plates of the machine.

In the drawings, accompanying and forming part of this description, the invention is explained by reference to specific structure, but it will be understood that the details may be modified in various respects without departure from the broad aspects of the invention.

Similar reference characters refer to similar parts throughout the drawings and the specification.

The machine shown in the drawings consists, in general, of a cleaning unit A, a tank unit B, and a hot air unit C.

2

Referring to Fig. 1, the cleaning unit A comprises a front wall 10, a back wall 11, side walls 12 and 13, a top wall 14, and an inclined bottom wall 15. The walls include a cleaning chamber 16, which is accessible from the outside to a vertically slidable door 17 and the front wall 10.

The interior of the cleaning chamber 16 contains an endless tumbling belt or conveyor 18, made of wire mesh so as to permit liquid or a stream of air to pass therethrough.

A suitable form of belt construction is shown in detail in Fig. 4. The belt comprises a plurality of transversely extending main rods 19 and intermediate rods 20. The wire mesh or webbing 21 of the belt is formed by wire 21 which is wound substantially in the form of a helix, around a main and intermediate rod, respectively, the helix being flattened so as to form a webbing having elongated links as is clearly apparent from the drawing.

The main rods extend to and form the bolts of side chains 22 of the Morse type having links 23 arranged in parallel pair and spaced by rollers 24 on the main rods 19.

The tumbling belt is trained around rollers 25, 26 and 27 and is guided by head plates 28, one at each side of the belt so as to form a trough 29, in which the parts to be cleaned may be placed. The rollers 25, 26 and 27 have shafts 30, 31 and 32, respectively, mounted in the side walls 12 and 13 of the cleaning unit A.

The head plates 28 are secured within the cleaning unit by bolts 33 and have secured thereto a guiding edge 34 on which the side rollers 24 of the conveyor ride.

Referring to the detailed illustration in Fig. 5, the guiding edge 34 is secured to the head plate 28 by bolts 35, the arrangement being such that the edge 36 of the head plate extends in close proximity over the links 23 of the side chain and far enough over the webbing of the tumbling belt as to prevent small parts from getting caught in the spaces between the webbing 21 and the side chain 22.

The tumbling belt is normally driven in the direction of the arrow 37, power being applied to the driven shaft 30 of the roller 25 through a chain 38, a variable reduction gear 39, and a belt 40 from a motor 41.

Washing liquid is directed into the trough 29 from a series of washing nozzles 42 in a spray head 43. Washing liquid is supplied to the spray head 43 through a conduit 44 extending from a main supply valve 45. A branch conduit 46 leads 55 from the conduit 44 to a lower spray head 47, ar-

ranged below the portion of the tumbling belt which forms the trough 29. The nozzles 48 in the lower spray head 47 are so directed as to discharge jets of liquid into the trough 29 through the previous tumbling belt 18. The strength of the jets issued from the lower spray head is adjustable by a valve 49 in the branch conduit 46.

Washing liquid issued from the spray heads 43 and 47 collects on the inclined bottom wall 15 and drains through a drain port 50 at the lowermost portion of the cleaning chamber A into the tank B below.

The tank B comprises front and back walls 51 and 52, side walls 53 and 54, respectively, and a bottom wall 55. The bottom wall 55 rests on a base 56 and slopes towards a flush and drain port 57.

The interior of the tank B is accessible from the outside through a door 58. Tracks 59 of angle iron extend from the door to the front wall 51 of the tank B. The tracks 59 support strainer baskets 60 and 61, releasably interconnected by a hook member 62. The strainer baskets have bottoms of wire mesh and filter the washing liquid passing through the drain port 50 of the cleaning unit A.

Washing liquid is withdrawn from the tank B through a suction port 63 surrounded by a screened container 64 to prevent impurities in the washing liquid from entering the suction port. A conduit 65 leads from the suction port 63 to the intake 66 of a pump 67, driven by a motor 68. The pump 67 has a discharge port 69 leading to a conduit 70 connected to the main supply valve 45.

The level of the liquid in the tank B is determined by an overflow trough 71 extending along the front wall 51 and the side wall 54 and leading to an overflow port 72 in the back wall 52 of the tank B.

A conduit 73 leads from the overflow port 72 to a drain pipe 74 connected to the sewer or another point of liquid disposal.

The flush and drain port 57 of the tank B is connected to a conduit 75 containing a drain valve 76, which in normal operation of the machine is closed. The valve 76 may be opened to drain the washing liquid from the tank and to remove impurities collecting at the bottom 55.

Impurities removed from the parts cleaned in the machine collect in the strainer basket 60 below the drain port 50 of the cleaning chamber 16. The strainer basket 60 may be removed from the machine for cleaning purposes while the machine is in operation. For this purpose, the door 58 is opened and the strainer baskets 60 and 61 moved towards the door until the basket 61 assumes the position normally occupied by the basket 60. The hook connection 62 between the two baskets 60 and 61 is then severed and the basket 60 removed from the machine for cleaning while basket 61 continued to filter the washing liquid.

After the cleaning, the basket 60 is placed back on the track 59, hooked onto the basket 61, and the basket assembly is then moved back into the position shown in Fig. 1.

The main supply valve 45 is operable from the front of the machine through an operating shaft 77 equipped with a hand lever 78 secured by a nut 79. The operating shaft 77 is supported in a bracket 80 mounted on the front wall 10 of the cleaning unit A.

A hand lever 78 is double armed and has an elongated slot 81 therein, engaging a pin 82 of a push bar 83. The push bar 83 is slidably supported on the bracket 80 at 84 and 85 and co-

operates with a tiltable latch member 86. The latch member 86 is pivotably mounted at 87, in such manner that its own weight causes it to tilt clockwise into the position shown in dotted lines in Fig. 2 if the latch member is free to do so after retraction of the push bar 83.

The latch member has an end surface 88 adapted to abut and block the end of the push bar 83 if the latch member is in the position shown in dotted line. The other end of the latch member 86 has projections 89 and 90 defining a space therebetween into which the end of a locking member 91 fits. The locking member 91 is secured to the sliding door 17 by bolts 92.

In the position shown in solid lines in Fig. 2 the door 17 is firmly locked in its closed position by the locking mechanism, the locking member 91 being held between the projections 89 and 90 of the latch member 86 which, in turn, is prevented from turning by the push bar 83. In this position the main supply valve 45 operable by the lever 78 is open and liquid is being discharged into the cleaning chamber A.

The door 17 may be opened only after shutting off the supply of liquid. This is done by moving the lever 78 of the supply valve 45 to the center or to the right as shown in dotted line in Fig. 2. In these positions the push bar 83 is retracted sufficiently to recede from underneath the tiltable latch member 86 which will then move into the position shown in dotted lines after opening of the door 17.

The latch member 86 remains in the tilted position owing to its own unbalance. In the tilted position it locks the push bar 83 and prevents an opening of the main supply valve 45 as long as the door is open.

When the door is moved towards its closed position the locking member 91 strikes the projection 89 of the tiltable latch member 86 and tilts the same, thereby unblocking the path of the push bar 83 and permitting free movement of the valve lever 78 to the right beyond the center position to open the valve 45. As the valve lever 78 is being moved beyond the center position, the push bar 83 moves underneath the end of the tiltable latch member 86, thus locking the door in its closed position.

The door 17 is provided with brackets 93 near its upper edge, having a pin 94 therein movable in an elongated slot 95 in one end of rods 96. The other end of the rods 96 is pivotally connected at 97 to a chute 98. The chute 98 is pivotally mounted at 99 to the front wall 10 of the cleaning unit A.

The door 17 may be moved in a vertical direction by a handle 100 secured to the door. As the door is being moved towards its open position, the pins 94 travel in the elongated slots 95 of the rods 96 until they reach the upper end of the slots. The rods 96 then move with the door causing the chute 98 to tilt and assume the position shown in dotted lines in Fig. 2 to permit the discharge of parts from the trough 39 of the conveyor 18.

A hot air unit C is mounted on one side of the cleaning unit A. The hot air unit consists in general of a housing 101 enclosing an air pump 102 driven by a motor 103. The housing 101 has an intake port 104 and an outlet port 105 to which intake and outlet air ducts 106 and 107 are connected. Valves 108 and 109 are arranged in the air ducts for opening and closing the air ducts at will. A by-pass duct 110 connects ducts 106 and 107 and contains a valve 111 for opening and closing the by-pass duct.

The valves 108, 109 and 111 are inter-connected by a shaft 112 and bevel gears 113 for joint operation. The shaft 112 extends through the ducts and carries at its rear end a pinion 114 whose teeth mesh with the teeth of a rack 115 at one end of a push rod 116 supported on a roller 117.

The rod 116 extends in the back of the machine and is connected to a lever 117 on an extension 77 of the operating shaft 77 of the main supply valve 45.

The position of the movable members of the valves 108, 109 and 111 and of the main supply valve 45, respectively is such that the air ducts 106 and 107 are closed and the bypass 110 is open while the main supply valve is open, its operating lever 78 being in the extreme right position. Washing liquid is then supplied to the washing nozzles 42 from the main supply valve while drying air may circulate through the by-pass duct 110.

When the hand lever 78 is moved into its center position, the main supply valve 45 is closed, the valves 108 and 109 are open admitting drying air into the cleaning chamber 16 while the bypass valve 111 is closed.

A movement of the hand lever 78 to the extreme left leaves the liquid supply valve 45 closed but causes air valves 108 and 109 to close and bypass valve 111 to open, thus shutting off the flow of drying air through ducts 106 and 107 so that parts may be placed into or removed from the cleaning chamber.

Air is withdrawn from the cleaning unit A through the intake air duct 106 connected to the top wall 14 of the cleaning unit A at a flange 118. The air withdrawn from the cleaning unit enters the hot air unit C and passes through the pump 102. Compressed air leaving the pump 102 passes through an electric air heater 119, the air supply duct 107 and enters the cleaning unit A at a flange 117. The air supply duct 107 continues inside the cleaning unit and leads to drying nozzles 118 arranged in air discharge heads 119.

The housing of the hot air unit is accessible through a door 123, which is normally tightly closed. An adjustable air port 124 is arranged in a side wall of the housing 101 to permit the pump 102 to withdraw supplemental air from the atmosphere to replace air leaving the cleaning unit through leaks in the sliding door 17 and at the tiltable chute 98, which forms in its upwardly tilted position the lower section of the door through which the cleaning chamber 16 is accessible.

A control lever 125 in the hot air unit operates electrical controls, not shown in detail, for starting and stopping of the pump motor 103 and for supplying electric current to the air heater 119.

The operation of the machine is as follows:

Parts to be cleaned are placed in the trough 29 through the open door 17, 98. The door is then closed causing the locking member 91 near the lower right hand corner of the door to engage the rotatable latch member 86 and to move the member into a position in which it will unblock the push bar 83 of the hand lever 78 which operates the main supply valve 45.

The motor 41 is then started to move the tumbling belt 18 in the direction of the arrow 37, causing parts in the trough 29 to be carried upwardly to a point where they will tumble down into the trough under the influence of gravity. 75

whereby all surfaces of the parts become exposed to the action of the washing liquid.

Washing liquid is admitted to the spray heads 43 and 47 by opening the main supply valve 45. The spray heads 43 and 47 discharge powerful jets of washing liquid against the tumbling parts from above and from below. The lower spray head 47 serves a triple purpose: It firstly sprays the parts in the trough through the mesh of the tumbling belt 18. Secondly, it cleans the belt as it passes over the spray head and, thirdly, it loosens up the parts in the trough. The strength of the jets issued from the lower spray head 47 is adjusted at the valve 49 to obtain a jet pressure not quite enough to blow the parts out of the trough, but sufficient to prevent the parts from packing too tightly in the trough, thereby facilitating the removal of impurities.

During the washing operation, the valves 108 and 109 in the air duct 106 and 107 remain closed. At the end of the washing period, the supply valve for the washing liquid is closed by moving the hand lever 78 into the center position. The movement of the hand lever 78 is transmitted to the air valves 108 and 109 through the push rod 112 opening the air valves.

Hot air will now be supplied to the air-discharge heads 121 issuing powerful jets of drying air against the parts tumbling in the trough 29 of the tumbling belt 18.

The drying operation is aided very effectively by the tumbling of the parts, causing the parts to be turned over continuously whereby drops of liquid are shaken off and cavities in the parts are emptied of washing liquid, which during the washing operation accumulated therein.

At the end of the drying operation the hand lever 78 is moved to the extreme left causing the flow of drying air to the cleaning chamber to be interrupted. The door 17 is then opened. The opening movement of the door causes discharge chute 98 to tilt downwardly as shown in dotted lines in Fig. 1. The parts resting in the trough 29 of the conveyor 18 may then be discharged by reversing the direction of the belt, causing the parts to climb over the roller 27 and to slide down the chute 98 into a receptacle.

The features and advantages of the invention are numerous.

The treatment of parts of the washing liquid while the parts are being tumbled on a previous belt provides a most efficient and rapid cleaning of the parts. All surfaces of the parts are reached by the washing liquid, and the cleaning of the parts is aided mechanically by the friction between the tumbling individual parts.

The provision of a lower nozzle aids in the washing operation by loosening up the parts, and facilitating the removal of impurities. In addition, the jets issued from the lower nozzle maintain the tumbling belt clean and prevent impurities from collecting in the mesh of the conveyor.

The tumbling of the parts during the drying operation greatly reduces the drying time and makes the machine particularly suitable for the cleaning of parts having cavities in which washing liquid tends to collect.

The provision of a two-section door the lower section of which is in the form of a discharge chute contributes substantially to the efficiency and economy of the machine making it unnecessary for an operator to handle the cleaned parts when removing them from the machine.

A further feature of the machine resides in the

fact that the washing and drying operation are carried out in the same chamber. This makes it unnecessary to employ two separate machines and to transport the cleaned parts from a washing to a drying machine. The provision of means for shielding the edges of the conveyor and the side chain makes the machine particularly suitable for the cleaning of small parts, such as screws, nuts, and the like.

Obviously the present invention is not limited to the specific embodiment herein shown and described. Other forms of tumbling belts may be employed and other means used for mounting or supporting the belt. The trough portion of the belt may obviously rest on rotatable supporting end disks instead of fixed end plates to reduce friction. Such modifications, substitutions, additions and omissions may be made, as will readily occur to persons skilled in the art. Such changes, however, do not involve a departure from the scope and spirit of the invention.

What is claimed is:

1. A cleaning machine comprising, in combination, an endless pervious belt trained around rollers, a section of the belt being curved so as to form a tumbling trough in a space of air adapted to receive parts to be cleaned; an upper nozzle above the trough portion of the belt adapted to discharge a jet of liquid under pressure into said trough and against parts therein; a lower nozzle below the trough portion of the belt adapted to discharge a jet of liquid under pressure against the underside of said belt and through said belt into said trough, so as to prevent parts from packing tightly in said trough; means below said belt for collecting liquid passing through said belt, said means including a tank; conduits for supplying said nozzles with liquid under pressure from said tank; a valve in the conduit leading to said lower nozzle; and means for driving said belt.

2. A cleaning machine comprising, in combination, a cleaning housing having an aperture; cleaning means in said housing; and a two-section door in said housing for closing said aperture, the door including an upper section vertically slidable in said housing and a lower section pivoted about a substantially horizontal axis and tiltable into a closed position in which the lower section cooperates with said upper section to close said aperture, and an open position in which it forms a downwardly inclined surface for the discharge of articles from said housing.

3. A cleaning machine comprising, in combination, a cleaning housing having an aperture; cleaning means in said housing; a two-section door in said housing for closing said aperture, the door including an upper section vertically slidable in said housing and a lower channel shaped section pivoted about a substantially horizontal axis and tiltable into a closed position in which the lower section cooperates with said upper section to close said aperture, and an open position in which it forms a downwardly inclined chute for the discharge of articles from said housing; and means for operatively connecting said upper and lower sections for joint movement into a closed position and into an open and discharge position, respectively.

4. A cleaning machine comprising, in combination, a tumbling belt; means for discharging jets of a pressure fluid against said belt; a supply valve for interrupting the flow of fluid to said jet means; a housing enclosing said belt and jet means and having an aperture, a two section door

in said housing for closing said aperture the door including an upper section vertically slidable in said housing and a lower channel shaped section pivoted about a substantially horizontal axis and tiltable into a closed position in which the lower section cooperates with said upper section to close said aperture and an open position in which it forms a downwardly inclined chute adapted to receive articles from said belt for discharge from said housing; means interconnecting said upper and lower sections for joint movement into an open and a closed position; and means for interlocking said door and said supply valve to prevent a discharge of fluid while the door is open.

5. A cleaning machine comprising in combination, a housing; a pervious belt guided in said housing for movement along a curved path so as to form a tumbling trough in a space of air adapted to receive in said trough parts to be cleaned; a nozzle for discharging a jet of liquid into said trough from above; a nozzle for discharging a jet of liquid into said trough through said belt from underneath; means for supplying a liquid to said nozzles; means below said belt for collecting liquid passing through said pervious belt; and means for driving said belt.

6. A cleaning machine comprising in combination, a housing; a pair of headplates in said housing; a pervious movable belt guided for movement along a guiding edge of said headplates, the guiding edge being so curved as to form a trough in said belt adapted to receive therein parts to be cleaned; a nozzle for discharging a jet of pressure fluid into said trough; a means for supplying pressure fluid to said nozzle; said headplates having a ledge adjacent to the belt guiding edge, said ledge extending substantially parallel with said belt for keeping parts in said trough from reaching the guiding edge of said headplates.

7. A combination washing and drying machine comprising in combination, a housing; a pervious belt mounted in said housing for movement along a curved part so as to form a trough adapted to receive in said trough parts to be cleaned; a nozzle in said housing for discharging a jet of liquid into said trough; a nozzle in said housing for discharging a jet of air into said trough; means below said belt for collecting liquid passing through said belt; an air duct for withdrawing air from said housing, said duct leading to said air nozzle; air heating means in said duct; air propelling means in said duct for propelling air through said duct and said heating means; and means for interrupting the flow of liquid to said air nozzle.

8. A combination washing and drying machine comprising in combination, a housing; a pervious belt mounted in said housing for movement along a curved part so as to form a trough adapted to receive in said trough parts to be cleaned; a nozzle in said housing for discharging a jet of liquid into said trough; a nozzle in said housing for discharging a jet of air into said trough; means below said belt for collecting liquid passing through said belt; and means for selectively supplying air under pressure to said air nozzle and liquid under pressure to said liquid nozzle, respectively.

9. A combination washing and drying machine, comprising in combination, a housing; a pervious belt mounted in said housing for movement along a curved path so as to form a trough adapted to receive in said trough parts to be cleaned; a nozzle in said housing for discharging a jet of liquid into said trough; a nozzle in said housing

for discharging a jet of air into said trough; means below said belt for collecting liquid passing through said belt; and air heating and propelling unit adjacent said housing, said unit communicating with the interior of said housing to withdraw air therefrom; a duct leading from said unit to said air nozzle; and means for selectively controlling the discharge of liquid and of air through the said liquid and air nozzles, respectively.

CHARLES HIRSCH.
